(57) **CLAIM**

The ornamental design for a feline lavatory, as shown and described.

DESCRIPTION

FIG. 1 is a top perspective view of a feline lavatory, showing my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is an exploded view thereof; and,

FIG. 10 is another top perspective view thereof.

Features shown in broken lines in FIGS. 1-10 illustrate portions of the feline lavatory that form no part of the claimed design.

1 Claim, 10 Drawing Sheets
